UNITED STATES PATENT OFFICE.

MARQUIS D. GROW, OF DUBUQUE, IOWA.

IMPROVEMENT IN WATER-WHEELS.

Specification forming part of Letters Patent No. **152,484**, dated June 30, 1874; application filed April 25, 1874.

To all whom it may concern:

Be it known that I, MARQUIS D. GROW, of Dubuque, in the county of Dubuque and State of Iowa, have invented a new and useful Improvement in Water-Wheel, of which the following is a specification:

Figure 1 is a detail vertical section of my improved water-wheel, taken through the line *x x x x*, Fig. 2. Fig. 2 is a top view of the same, part of the cap-plate or cover being broken away.

Similar letters of reference indicate corresponding parts.

My invention has for its object to furnish an improved water-wheel which shall be so constructed as to utilize the greatest possible amount of the power of the water, furnish a free discharge for the water, enable the entrance of the water to be fully controlled, and the gates to be easily operated.

The invention will first be fully described, and then pointed out in the claims.

A is the case of the wheel, in the upper part of which are formed the chutes *a*¹, to conduct the water to the buckets of the wheel B, which wheel fits into the interior of the case A, and is attached to the shaft C. The lower end of the shaft C revolves upon a step in the center of the cup D, formed upon or attached to the spider E, the ends of the arms of which enter a ring-groove in the lower part of the case A, notches being formed in said case to enable the spider to be removed by turning it partly around. *b*¹ are the buckets, which are made straight and radial, and are formed upon or attached to the body of the wheel B. *b*² are the discharges or issues, which extend rearward from the lower ends of the buckets *b*¹, and are curved downward as shown in Fig. 1, so as to be convex upon their upper side, as shown. The convex issues *b*² are surrounded by a band, *b*³, attached to or formed upon their outer edges, and the upper edge of which rests against the shoulder *a*², formed by the thickening of the case A for the chutes *a*¹, so that the water from said chutes may be discharged directly against the buckets *b*¹. By this construction the full force of the water will be exerted upon the buckets *b*¹ until its forward movement is stopped, and its full weight will then act upon the issues *b*² to drive the wheel forward, so that the whole power of the water will be utilized. Upon the outer side of the case A, a little be-

low the chutes *a*¹, is formed a flange, *a*³, upon which rests the main gate F, through which are formed openings corresponding in shape and position with the outer ends of the chutes *a*¹, so as to form continuations of said chutes. To the top of the gate F is bolted a ring, G, which fits around the edge of the top or cap plate H, in bearings in the center of which the shaft C revolves. To the cap H are pivoted at their angles two elbow-levers, I, the outer arms of which have short longitudinal slots formed in them to receive the pins J, attached to the ring G. To the other arms of the levers I, near their outer ends, are pivoted the ends of a connecting-bar, K, so that the levers I may operate together upon the opposite parts of the ring G to move the gate F.

By this arrangement the gate F will be moved without any side draft, and, consequently, with much less friction than when the power is applied at one side of the gate only.

Upon the outer end of one of the connected arms of the levers I is formed a toothed rack, *i*, to receive the pinions of the hand-wheel shaft for adjusting the gate. Upon the lower part of the outer side of the gate F is formed a flange, *f*', upon which rests the outer gate L, which has a flange, *l*', formed upon the lower part of its outer side, in one part of which are formed teeth *l*', into which is geared a governor, so that the gate L may be adjusted automatically to regulate the ingress of the water by the motion of the wheel, which motion is controlled by the resistance encountered, or, in other words, by the amount of machinery to be driven by said wheel.

Having thus described my invention, I claim as new and desire to secure by Letters Patent—

1. The radial buckets *b*¹, having convex discharge-surfaces *b*², surrounded by a band, *b*³, as shown and described, for the purpose specified.
2. The combination of outer gate L and inner gate F, the former resting upon a flange, *f*', of the latter, and having a flange, *l*', as and for the purpose set forth.
3. The combination of the bent levers I and connecting-bar K with the main gate F and the top or cap plate H of the casing, substantially as herein shown and described.

Witnesses: MARQUIS D. GROW.

HENRY KOLB,
JOHN McGOVERN.
